United States Patent

Des. 239,460
Patented Apr. 6, 1976

239,460

LIGHTING FIXTURE

Arthur Schacht, East Hills, N.Y., assignor to Crystal Mart, Inc., Deer Park, N.Y.

Filed Oct. 30, 1974, Ser. No. 519,281

Term of patent 14 years

Int. Cl. D11—02; D26—05
U.S. Cl. D48—23 R

FIG. 1

FIG. 2

FIG. 3

FIG. 4

FIG. 5

FIG. 1 is a perspective view of a lighting fixture showing my new design;

FIG. 2 is a top plan view thereof;

FIG. 3 is a right side elevation view thereof;

FIG. 4 is a rear side elevation view thereof;

FIG. 5 is a bottom plan view thereof.

The broken lines are shown in FIGS. 1, 2 and 5 for illustrative purposes only.

I claim:

The ornamental design for a lighting fixture, substantially as shown and described.
